WASHING MACHINE

Maurice J. Broderick, Chicago, Ill.

Application March 2, 1955, Serial No. 491,603

4 Claims. (Cl. 68—22)

This invention relates to washing machines and is particularly concerned with a washing machine with inbuilt wringer.

The principal purpose of the invention is to provide a highly efficient, compact large-capacity washing machine of pleasing appearance, for use, generally speaking, in any ordinary households but especially in relatively crowded conditions, as in modern apartments or the like, requiring relatively little space and being mobile so that it may be respectively used and stored away in any desired and suitable location. The machine of the invention may for example be used in a kitchen of ordinary size and stored away in a clothes-closet; it may likewise be permanently placed in a kitchen or the like, always ready for service, and during nonuse, it may serve in the nature of a hamper. Its pleasing appearance will blend well with other appliances ordinarily found in kitchens or the like.

Some of the salient objects of the invention are outlined below so as to aid the understanding of the detailed explanations which are to follow.

One object is to provide a washing machine of the above outlined type which has been designed with a view of ease of manufacture and assembly, using numerous readily obtainable standard parts combined in novel manner with other parts so as to produce a highly efficient reliably and economically operating structure.

Another object is to incorporate in the machine, as an integral part thereof, a wringer disposed directly adjacent to the washing compartment and in direct communication with such compartment. A reversible drive comprising a standard reversing gear is provided for the wringer so as to permit feeding objects into the washing compartment as well as discharging them from such compartment under pressure so as to remove liquid therefrom which drains back into the washing compartment. Washed objects are in this manner efficiently discharged from the washing compartment in a damp condition, ready for ironing or drying without spilling liquid outside the machine.

A further object is to provide a wringer comprising a drive roller in driving coaction with the standard reversible gear, and a driven roller for coaction with the drive roller. The driven roller is part of a subassembly or unit, and means is provided for removably locking or latching such subassembly or unit to stationary parts of the drive roller, so as to dispose the driven roller for resilient pressure-coaction therewith. Release of the locking or latching means causes instant release of the subassembly, thereby instantly releasing the driven roller from pressure-coaction with the drive roller and thus providing for a safety feature to prevent accidents and/or damage due to jamming of the wringer.

Still another object is to provide an inner tub forming in its lower portion a cross-sectionally generally square rectangle and in its upper portion a cross-sectionally somewhat elongated rectangle having a shelflike bottom wall offset from the lower tub portion and merging with

2

the corresponding downwardly extending side wall thereof. The upper portion of the tub which is thus laterally offset from the lower portion forms the wringer compartment, that is, a compartment for accommodating the wringer and its above indicated component parts. Wall means is provided for covering the wringer compartment and thereby the parts disposed thereon, except the wringer rollers, such wall means extending on the inside of the structure substantially in alignment with the corresponding wall of the lower tub portion. The lower cross-sectionally substantially square tub portion is thus extended upwardly substantially to the top of the structure, forming a cross-sectionally generally square washing compartment in which is disposed an agitator of standard design extending upwardly from the bottom wall thereof. The cross-sectionally substantially square configuration of the washing compartment provides for a large volumetric capacity and for increased turbulence of the washing liquid responsive to operation of the agitator, thus contributing to efficient operation.

The inner tub may be made of any desired and suitable material, for example, aluminum or stainless steel, and a drain may be provided in the bottom thereof. An outer shell of a suitable sheet material may be wrapped about the walls of the inner tub forming a unitary structure therewith and forming the casing of the machine. A lid is provided for removably covering the machine on the top thereof.

In accordance with a further object there is provided underneath the bottom wall of the inner tub a sturdy spiderlike supporting and mounting member. This member has the dual function first, of securely supporting the inner tub and second, of supporting standard operating elements mounted thereon and depending therefrom. These elements include the drive motor, a gear box and a pump. The gear box contains known gear means for driving the agitator and the reversible drive gear wheel for the wringer.

The motor drives the main gear in the gear box through the medium of a standard belt drive. The pump is pivotally mounted on a part extending from the supporting and mounting spider and carries a friction drive wheel for engagement with the belt. Brackets are provided inside of the casing near the bottom thereof, carrying suitable supporting means such as caster wheels. The spider member is rigidly connected with such brackets by sturdy posts extending downwardly therefrom and the entire weight of the inner tub and of the operating elements is thus transferred to the supporting brackets and therewith to the casters in engagement with the floor.

Control elements are provided on the outside of the casing of the machine including, first, a knob or the like for throwing the agitator into and out of gear by suitable clutch means; second, a knob or the like for actuating the reversible wringer drive gear respectively into neutral position and in position to drive the drive roller of the wringer in one or the other direction; and third, a knob or the like for moving the pivotally mounted pump so as to throw the friction wheel thereof into engagement with the drive belt, upon conclusion of a washing cycle, for the purpose of draining the liquid from the inner tub and moving it to a discharge from which it may be expelled through a hose or the like to any suitable place, for example, a sink.

A basketlike container is in accordance with the invention carried on the outside of the casing of the machine for holding the electric cord with its plug provided for establishing the current supply over a suitable wall socket or the like.

The above outlined and other objects and features of the invention will become apparent from the detailed de-

scription of an embodiment which will presently be rendered with reference to the accompanying drawings. In these drawings,

Fig. 1 is an elevational front view of an embodiment of the new washing machine;

Fig. 2 shows a side elevation of the machine;

Fig. 3 illustrates the machine in perspective view with the lid or cover removed;

Fig. 4 is a plan elevational view looking into the machine from the top;

Fig. 5 represents a view looking from the bottom of the machine upwardly at the operating elements depending from the supporting and mounting spider which is interconnected with the corner brackets carrying the caster wheels;

Fig. 6 shows the drive roller assembly of the wringer as seen when looking down after removal of the driven roller assembly;

Figs. 7 and 8 are sectional partial views taken respectively along lines 7-7 and 8-8 in Fig. 6 to illustrate stationary latching and locking parts for the assembly of the driven wringer roller unit;

Fig. 9 is a sectional view through the frame of the driven roller unit taken approximately along lines 9-9 in Figs. 4 and 10;

Fig. 10 shows a sectional view through the frame of the driven roller unit taken approximately along line 10-10 of Fig. 9;

Fig. 11 illustrates a sectional view of the driven roller unit taken approximately along line 11-11 of Fig. 9; and

Fig. 12 comprises two figures to aid in explaining the latching or locking of the driven roller unit, the coaction of the two wringer rollers, and the safety release of the unit.

Referring now to the drawings, numeral 1 indicates the outer shell or casing of the machine which extends substantially from the bottom to the top thereof. This casing may be enameled on the outside in desired color, for example, white, and a bottom portion 2 may be of a darker shade. This provides a distinctive appearance and has a utilitarian aspect in that it conceals splashes of dirt or wear marks that may be caused by handling. Numeral 3 (Figs. 3, 7 and 8) indicates a side wall of the inner tub having an inner wall 4 (Figs. 2, 3, 4, 5, 6) extending upwardly from its bottom wall 5 (Figs. 1, 2, 4, 5 and 6) and terminating in a laterally extending shelf 6 as indicated in Figs. 1, 2, 3, 4 and 6. The upper edges of the side walls of the inner tub and of the outer shell are connected by a border strip 7. A similar strip may be provided at the bottom, if desired.

The laterally offset wall 6 of the inner tub provides on top of the machine a transversely extending compartment for accommodating the various component parts of the wringer and its drive mechanism. These parts are in the operating condition of the machine concealed by the inner plates 8 and 9, plate 8 having lips 10 and 11 extending toward the wringer rollers, the wringer drive mechanism contained in the box 17 (Fig. 6) being covered on top by the plate 13. Numeral 14 indicates the top plate of the unit comprising the driven wringer roller 15 coacting with the drive wringer roller 16 operated from the standard reversing gear contained in the box 17.

It will be seen, therefore, that the inner tub which may be made for example of aluminum sheet forms within the outer shell or casing a washing compartment which is in its lower portion of cross-sectionally generally square configuration, such configuration being preserved in its upper portion where it is along one side defined by the inner walls or plates 8 and 9 covering the wringer drive compartment while leaving the wringer rollers 15 and 16 accessible and in free communication with the washing compartment.

The bottom 5 of the inner tub carries a drain 20 (Fig. 4) communicating with a fitting 21 (Fig. 5) disposed underneath, the fitting 21 being provided with a hose 22

extending to the intake of the pump 23 which is pivotally mounted at 24. Another hose 25 extends from the pump 23 to the fitting 26 shown in Fig. 1. A knob 27 is provided for angularly displacing the pump 23 which carries a friction drive wheel 28 so as to cause such drive wheel to engage the belt 29 driven by the motor 30 and driving the gear drive wheel 31, thereby causing actuation of the pump 23, upon conclusion of a washing cycle (the motor 30 being assumed to be in operation) for the purpose of draining the liquid from the washing compartment and moving it by way of the hose connection 25 to the fitting 26. A suitable hose may be connected with the latter fitting for discharging the liquid into a sink or the like.

15 The gear casing 35 shown in Fig. 5 may be a standard part as previously mentioned. Its main drive gear is driven by the motor 30 over the belt 29 and the wheel 31 to drive through the medium of suitable intermediate gears (not shown) a shaft 36 for the agitator 37 which 20 is disposed in the washing compartment above the bottom wall 5 thereof as shown. The agitator may also be a standard part and, like other standard parts used, such as the motor 30, the gear box or assembly 35, the pump 23 and the reversing gear 17, need not be described in 25 detail as the structure and function of such standard parts is well known. The gear assembly 35 also includes a gear for driving a shaft 40 extending vertically for driving the reversing gear contained in the box 17 shown in Fig. 6.

30 It should be observed that the wall 4 of the inner tub forms with the outer shell or casing a vertically upwardly extending space as shown at the right hand part of Fig. 5, such space terminating in the lateral shelflike wall 6 on top of which is disposed the wringer and its component 35 parts. Through this space extends the drive shaft 40 for the reversing gear 17 and also the discharge hose 25 from the pump to the fitting 26.

The known standard parts including the motor 30, the 40 gear assembly 35, and the pump 23 are mounted on and depend from a sturdy spiderlike supporting and mounting member disposed underneath the bottom wall 5 of the inner tub. This mounting member has arms 45 extending from a central portion 46 and side arms 47 and 48. From the junctures of the arms 45/47 and 54/48 extend 45 sturdy bolts 49 and 50, respectively, which connect respectively with the brackets 51 and 52 disposed inside the casing at the bottom corners thereof. Similar bolts 53 and 54 extend respectively downwardly from the side arms 47 and 48 connecting respectively with the corner brackets 55 and 56. A caster wheel such as shown at 50 57 is connected with each corner bracket.

It will be apparent, therefore, that the spiderlike mounting member supports the weight of the inner tub as well as the various operating elements including the 55 motor 30 which is secured to the spider by means of the mounting 60, the gear assembly 35 and the pump 23 which is pivotally mounted at 24 in journal members extending from a bracket 61 extending from the spiderlike member; the spiderlike member being in turn connected 60 with the corner brackets 51/52, 55/56 carrying the casters such as 57, and the weight of all parts is thus transferred to the casters in contact with the floor. There is accordingly no particular stress or strain put on any part that may be detrimental to its function.

65 It is understood, of course, that the drive shaft for the agitator extends upwardly through the bottom wall 5 of the inner tub through a liquid-tight journal which may be a standard part of known and approved structure. Underneath the bottom wall 5 of the inner tub is provided a suitable clutch of standard construction for coupling the agitator shaft in driving engagement with the gear actuated shaft 36 (Fig. 5). The corresponding clutch actuator may be a suitably pivotally mounted forked member 70 cooperating with a crank 71 journaled 70 in the arms of the journal member 61 depending from or

forming part of the spiderlike supporting or mounting member. The crank shaft 72, extends to the outside and may be actuated by a knob 73. Rotation of the knob 73 will cause rotation of the crank 71 and corresponding displacement of the clutch fork 70 so as to couple the agitator 37 for drive engagement with the gear driven shaft 36 or to disengage it, as desired.

The current on-off switch may be combined with the agitator on-off drive or with another control or, if desired, a special switch may be provided and disposed as may be desired.

The wringer, its component parts and operation as well as the locking or latching of the driven wringer roller relative to the drive roller and its release will be described next particularly with reference to Figs. 6 to 12.

Details of the assembly or unit of the driven wringer roller 15 are apparent from Figs. 9, 10 and 11. This unit, comprising a cover plate 14 and parts associated therewith including the driven roller 15 is removable from the machine in a manner which will be presently described in detail.

Fig. 6 shows the assembly or mounting of the wringer drive roller 16 as seen in plan elevational view when looking down after removal of the driven roller unit. At the left of the drive roller mounting is disposed the box 17 containing the known previously mentioned standard reversing gear driven by the shaft 40 from a gear in the gear box 35 (Fig. 5) the gears of which are in turn actuated by the motor 30. As noted before, the shaft 40 for driving the reversing gear 17 extends upwardly through the lateral space between the wall 4 of the inner tub and the corresponding wall of the outer casing. This space terminates at the shelflike laterally offset wall 6 of the inner tub as indicated in dotted lines in Fig. 2. The shaft 40 extends of course through the wall 6 into the reversing gear box 17. This gear box is normally covered by the plate 13 (Figs. 3 and 4) which is assumed to have been removed in Fig. 6.

The mounting for the driven wringer roller 16, as diagrammatically shown in Fig. 6, comprises a casting forming end walls 75, 76 having arms 77 and 78 respectively extending therefrom, such arms respectively forming angular inwardly and outwardly directed extensions 79 and 80. The outwardly directed extensions 79 and 80 project outwardly through a cutout in the casing formed by corresponding parts of the inner tub 3 and the outer shell 1 (see also Fig. 7) and terminate on the outside in flanges 79' and 80'. The inwardly directed portions of the extensions 79 and 80 stop short of the drive wringer roller 16. Numeral 81 indicates a forwardly extending curved apronlike member defining the lower edge of the frontal opening giving access to the wringer rollers 15 and 16, as is particularly apparent from Fig. 1.

At the rear of the drive roller mounting is secured the cover plate 8 forming a cutout defined by the curved lip 10 and similarly curved side arms 11. The lip 10 and the side arms 11 project forwardly and stop short of a line defined by the circumference of the drive roller 16 as particularly shown in Fig. 6. The side arms are respectively in alignment with the inwardly directed portions of the extensions 79 and 80. Numerals 83 and 84 indicate bosses formed by the casting forming the end walls 75 and 76 for securing the cover plate 8 in position. This cover plate 8 thus defines, as particularly shown in Fig. 3, an opening through which the wringer rollers 15 and 16 communicate with the washing compartment.

It should be observed that all edges formed by the openings in front as well as in the rear of the wringer rollers are well rounded to facilitate manipulation of pieces of laundry and to prevent damage thereto.

It will be seen from the foregoing explanations that the mounting means for the drive wringer roller forms two rectangular areas, one being well defined by the end wall 75, extension 77 with its rearward arm 79, and part of the rear cover plate 8 with its extension 11, and the

other rectangular area being well defined by the end wall 76, extension 78 with its rearward arm 80' and part of the rear cover plate 8 with its extension 11. These well-defined areas at the opposite ends of the mounting are provided for receiving the corresponding ends of the driven wringer roller unit shown in Figs. 9 to 11 in a manner which will be presently described.

At the bottoms of each of these well-defined areas is disposed a pair of bosses respectively shown at 85/86 and 87/88 each pair forming a recess for receiving a bearing such as shown at 90 and 91. Each bearing may be made of wood or the like for journaling corresponding portions of the shaft 92 of the wringer drive roller 16.

The left end of the shaft 92 extends through the end wall 75 of the mounting into the box 17 containing the reversing gear. Such gear may be of known standard construction comprising a bevel gear keyed to the shaft 92 and coaxial bevel gears which may be selectively coupled therewith by known clutch means providing for a neutral position and two operating positions, one for driving the drive roller 16 in one and the other for driving it in another direction of rotation. A knob 95 is provided on the outside of the casing for controlling the desired coupling of the gear with the bevel gear of the shaft 92 of the wringer drive roller 16. The knob 95 may be put in neutral position in which the wringer drive is disconnected or, as desired, for forward drive to discharge laundry pieces from the washing compartment or for reversed drive to feed laundry pieces into the washing compartment.

Each end wall 75 and 76 of the mounting for the wringer drive roller 16 is provided with an angular recess or notch as shown in Figs. 6, 7 and 8 respectively at 96 and 97. These notches are provided for receiving cross-sectionally semispherical portions 103 and 104 of a locking or latching shaft 105 of the cooperating driven wringer roller unit shown in Figs. 9 to 11. On the end wall 75 of the mounting shown in Fig. 6 is pivotally mounted a locking or latching pawl 98, as is particularly apparent from Fig. 7, and this pawl is biased in counterclockwise direction by a spring 99. The pawl is provided with an angular locking or latching tooth 100 projecting laterally inwardly of a line defined by the long side wall of the notch 96 in the end wall 75.

It will be clear from the above explanations that the semispherical portions 103 and 104 can be respectively inserted into the notches 96 and 97 in the end walls or plates 75 and 76 of the mounting shown in Fig. 6. Insertion of the corresponding semispherical portion into the notch 96 of the end plate 75 will move the tooth 100 of the pawl 98 to the right (as seen in Fig. 7) angularly rotating the pawl clockwise. Upon rotating the shaft 105 (Figs. 9 and 10) clockwise, the semispherical portions 103 and 104 will rotate into locking position in the notches 96 and 97 and the pawl 98 will be able to rotate counterclockwise into the position shown in Fig. 7 to lock the corresponding semispherical portion 103 and therewith the shaft 105 against displacement from the mounting for the wringer drive shaft.

Details of the above indicated locking operation and of the release of the assembly of the driven wringer shaft carrying the locking shaft 105 will be presently described with reference to Fig. 12 after next describing the structure of such assembly or unit with reference to Figs. 9 to 11.

The unit comprises a casting forming the top plate 14 (see also Fig. 4) having a rear wall 110 (see also Fig. 3) and a front wall 111 (see also Fig. 1). The horizontal portion of the top plate 14 overlapping the front wall 111 as shown in Fig. 11 corresponds to one of the forwardly directed ears of the top plate 14 as shown in Fig. 4. The locking shaft 105 is journalled in bosses 112, 113 provided thereon. End wall members 114, 115 are integral with the top plate casting. Each of these end wall members is provided with a cutout as indicated in Fig. 11 at

116. At the left of the end wall 114 is disposed a cross member 117 having an upward extension 118 provided with a slot 119. This cross member is secured to bosses on the under side of the top plate 14 by means of screws 120, 121. Compression springs 122 and 123 are respectively associated with the screws 120, 121. The left hand end 125 of the shaft 105 of the driven wringer roller 15 is disposed in the slot 119 formed in the upwardly extending arm or part 118 of the cross member 117.

The journal for the right hand end 126 of the shaft of the driven wringer roller (see Figs. 9 and 10) corresponds in all details to the structure for journaling the left hand end 125 of the shaft as described above.

The locking shaft 105 extends to the left of the left hand journal structure. A handle 130 is rotatable on the corresponding end of the shaft 105. A pin 131 extends from the shaft 105 into an elongated slot 132 formed in the handle journal portion. It follows, therefore, that the handle 130 can rock on the shaft 105 within the limitations of the slot 132. Putting it in other words, if it is assumed that the handle 130 is rotated out of the position in which it is shown in Fig. 10, that is, perpendicularly out of the plane of the drawing, it will first rotate freely on the shaft 105 until the rear wall of the slot 132 engages the pin 131; further rotation of the handle will rotate the shaft 105 correspondingly. The operation in the other direction is similar. The arrangement produces in this manner a lag in the operation of the shaft, the rotation thereof lagging somewhat behind the rotation of the handle. The journal portion of the handle is provided with a camming pin 135. The locking shaft 105 is reduced at its opposite ends to form the previously mentioned semispherical portions 103 and 104.

The insertion of the unit of the driven wringer roller with the drive wringer roller, the locking of such assembly in operating position and the safety release thereof will now be described with reference jointly to Figs. 6 to 11 and particularly with reference to Fig. 12.

The assembly or operating unit of the driven wringer roller 15 shown in Figs. 9 to 11 is inserted into the structure shown in Fig. 6 with the opposite ends forming the journals for the shaft ends 125 and 126 (Fig. 9) taking their places within the well-defined areas at the opposite ends of the mounting for the drive wringer roller 16. The handle 130 is during such insertion in the position shown in Figs. 9 and 10 and also indicated in full lines in Fig. 12. The semispherical portions 103 and 104 of the locking shaft 105 are accordingly in the positions indicated in full lines and easily slip into the notches 96 and 97, respectively, also shown in Figs. 7 and 8. Pressure is thus placed on the tooth 100 of the pawl 98 and such pawl rotates clockwise into the full line position shown in Fig. 12. The handle 130 is thereupon rotated clockwise into the dotted line position shown in Fig. 12 (perpendicularly out of the plane of the drawing as shown in Fig. 9) to rotate the shaft 105 by 45° so as to place the semispherical reduced shaft portions 103 and 104 into the full line position shown in Fig. 12 in connection with the portion 103. These portions accordingly lock within the notches 96 and 97 in an obvious manner. The pawl 98 can now rotate clockwise into the dotted line position shown in Fig. 12, thereby locking the assembly or unit of the driven wringer roller 15 in place above and for coaction with the drive wringer roller 16.

The ends 125 and 126 of the driven roller 15 are disposed in the slots such as 119 formed in the upward extensions such as 118 of the respective cross members such as 117. Accordingly, when the driven wringer roller 15 engages the drive wringer roller 16, the ends 125, 126 of its shaft will move upwardly within the slots 119 into the position in which the shaft end 125 is shown in Fig. 12. The wringer rollers 15 and 16 are now in engagement and the driven roller 15 is locked in coacting position with the drive roller 16 by the locking of the semispherical portions 103 and 104 of the locking shaft 105 in the notches 96, 97

of the end plates or walls of the mounting for the drive wringer roller, all as described as before.

Assuming now that the washing operation is to be started, the tub being assumed to be filled with washing liquid, the motor is turned on and the knob 73 is actuated to operate the clutch fork 70 (Fig. 5) so as to couple the agitator shaft with the corresponding drive gear in the gear assembly 35. The laundry pieces may be put into the tub from above after removing the lid 140 or they may be fed thereinto through the wringer rollers. In the latter case, the knob 95 is actuated to couple the drive wringer roller 16 with the in-feed gear of the reversing gear and the laundry feed-in operation can proceed. In most cases it will probably be preferred to place the laundry pieces to be washed directly into the tub. The feed-in operation by means of the wringer is however possible and therefore has been described.

Upon completion of the washing operation, the corresponding laundry pieces may be removed through the wringer. This is done by first actuating the knob 95 so as to couple the shaft 92 of the drive wringer roller 16 with the gear 17 for feed-out rotation of the roller. The individual laundry pieces are thereupon fed to the wringer and ejected therefrom in damp condition ready for drying or ironing as the case may be. The liquid may thereupon be drained from the tub by actuating the knob 27 so as to operate the pump 23 for the purpose of draining the tub and ejecting the liquid at the fitting 26 to which may be connected a hose leading to a sink or the like.

The pressure wringing operation will be appreciated from a consideration of the right hand drawing of Fig. 12. Assuming an object is inserted into the wringer between the rollers 16 and 15, such object will tend to pry these rollers apart. The resulting pressure is propagated to the driven wringer roller 15, and inasmuch as the ends 125, 126 of such roller are in their locked positions in engagement with the upper margins of the slots such as 119 in the extension 118 of the respective cross member such as 117, such pressure will tend to lift these cross members against the pressure of the associated compression springs such as 122 and 123. These compression springs accordingly supply the wringer pressure.

The ends 125 and 126 of the shaft of the upper driven wringer roller can move upwardly within the slots such as 116 in the walls 114 and 115 extending downwardly from the top plate 14. Allowance is accordingly made for the passage of laundry pieces of different thickness.

It shall now be assumed that the wringer jams for some reason or that the operator's hand is just about to become caught between the wringer rollers by awkward handling. Release of the wringer and in the latter case instant release must be effected so as to avoid damage or injury.

The instant release is effected by throwing the handle 130 from the dotted line position in Fig. 12 to the full line position in which the handle 130 is also shown in Figs. 3, 4, 9 and 10. The handle rotates initially freely on the locking shaft 105 until the slot 132 catches up with the pin 131. During this initial rotation, the pin 135 extending from the handle journal, engages the cam portion 101 of the pawl 98 (see left hand drawing in Fig. 12) pressing upon the cam 101 and thereby rotating the pawl 98 clockwise from the locked dotted position in Fig. 12 to the full line release position in which the tooth 100 of the pawl is disengaged from the flat section of the semispherical portion 103 of the locking shaft 105. Further rotation of the handle will carry along the shaft 105 to put the semispherical portions into the full line positions shown in the left hand drawing of Fig. 12. The pressure of the pairs of compression springs such as 122, 123 can now exert itself and the upper unit carrying the driven roller 15 can snap upwardly into released position in which there is no pressure on the wringer rollers and in which position the driven wringer roller unit can be removed.

Numerical 150 in Figs. 1, 2 and 4 indicates a basketlike

receptacle for storing away the electric cord 151 with its plug 152 when the machine is not used.

It is, of course, understood that the washing operation may be carried out in several stages, for example, first, one or more washing stages and, second, one or more rinsing stages. The tub may be drained as described at the conclusion of each stage and filled with fresh liquid for the next stage. The entire washing operation is, for example, concluded upon conclusion of the last rinsing stage and the corresponding laundry pieces may then be removed through the wringer to extract the liquid therefrom as described before.

The members covering parts of the wringer mechanism on the inside of the machine have been shown with their margins or edges in abutment with respectively adjacent parts. It is clear, of course, that some or all of these members may be slightly spaced from adjacent parts so as to provide for drainage of liquid from the wringer back to the washing compartment; alternatively, apertures may be formed in such or corresponding members or elements wherever they may be required or desired to provide for efficient drainage of liquid from the wringer.

Changes may be made within the scope and spirit of the appended claims.

I claim:

1. In a washing machine having means forming a washing tub, a wringer mechanism comprising a first relatively stationary unit including a rotatable positively driven driving roller, a second unit comprising a shaft carrying a driven roller, a pair of spaced apart bearing members for respectively journaling the opposite ends of said shaft, spring biased means for floatingly mounting each bearing member, and a device for releasably disposing said second unit with said driven roller in resilient pressure drive engagement with said driving roller, said device comprising relatively stationary camming means extending from said first unit, a movable locking member carried by said second unit for coaction with said camming means, lever means for moving said locking member in a predetermined direction into interlocking engagement with said camming means, a spring biased pawl for securing said interlocking engagement, and means actuated by said lever means upon movement thereof in opposite direction for first releasing said pawl and thereafter moving said locking member out of interlocking engagement with said camming means to release said driven roller from pressure drive engagement with said driving roller; said locking member being a rotatable shaft having spaced apart semispherical portions formed thereon for camming coaction with notches formed in correspondingly spaced apart stationary members of said first unit and forming said camming means, said lever means being rotatable on said shaft, a pin extending from said shaft radially thereof for disposal in an elongated slot formed in said lever, rotation of said lever in either direction effecting lagging rotation of said shaft, and means

carried by said lever for camming coaction with said pawl during the interval of free rotation of said lever on said shaft.

2. In a washing machine, means forming an outer cross-sectionally substantially rectangular casing, means forming in said casing a cross-sectionally substantially square tub, a wringer mechanism extending transversely along one side of said casing substantially at the top thereof, said wringer mechanism comprising a pair of rollers disposed in direct communication with said tub, and a relatively stationary frame for mounting one of said wringer rollers, said frame forming outwardly directed arms for defining an opening giving access to said rollers from the outside of said casing.

3. In a washing machine, means forming an outer cross-sectionally substantially rectangular casing, means forming in said casing a cross-sectionally substantially square tub, a wringer mechanism extending transversely along one side of said casing substantially at the top thereof, said wringer mechanism comprising a pair of rollers disposed in direct communication with said tub, a relatively stationary frame for mounting one of said wringer rollers, said frame forming outwardly directed arms for defining an opening giving access to said rollers

25 from the outside of said casing, and a cover plate for parts of said wringer mechanism facing said tub, said cover plate forming arms for defining an opening giving access to said rollers.

4. In a washing machine, means forming an outer cross-sectionally substantially rectangular casing, means forming in said casing a cross-sectionally substantially square tub, a wringer mechanism extending transversely along one side of said casing substantially at the top thereof, said wringer mechanism comprising a pair of rollers disposed in direct communication with said tub, a relatively stationary frame for mounting one of said wringer rollers, said frame forming outwardly directed arms for defining an opening giving access to said rollers from the outside of said casing, a cover plate for parts of 30 said wringer mechanism facing said tub, said cover plate forming arms for defining an opening giving access to said rollers, and a frame for removably mounting the other one of said rollers, said last-named frame forming lips respectively at the front and the rear thereof for defining 35 arms for defining an opening giving access to said rollers from the outside of said casing, a cover plate for parts of 40 said wringer mechanism facing said tub, said cover plate forming arms for defining an opening giving access to said rollers, and a frame for removably mounting the other one of said rollers, said last-named frame forming lips respectively at the front and the rear thereof for defining 45 the upper margins of the respective openings formed respectively by the arms of said frame and said plate.
